(57) **CLAIM**

The ornamental design for a combined medicine container and cap, as shown and described.

DESCRIPTION

FIG. 1 is a bottom perspective view of a combined medicine container and cap;

FIG. 2 is a bottom plan view thereof;

FIG. 3 is a left side view thereof;

FIG. 4 is a front side view thereof;

FIG. 5 is a right side view thereof;

FIG. 6 is a rear side view thereof; and,

FIG. 7 is a top view thereof.

The combined medicine container and cap is shown with a symbolic break in its length. The appearance of any portion of the article between the break lines forms no part of the claimed design.

The broken lines depict broken portions of the article that form no part of the claimed design.

1 Claim, 7 Drawing Sheets
